REELING DEVICE

UNITED STATES PATENT OFFICE

Patented Dec. 18, 1951
2,579,291
REELING DEVICE

Lester W. Ballou, Attleboro, Mass., assignor to Ballou & Boss, Inc., a corporation of Rhode Island

Application May 16, 1950, Serial No. 162,300

5 Claims. (Cl. 242—107)

1

This invention relates to a reeling device of the type used for attaching articles to the clothing, such for instance as eye glasses, pencils, or the like, in which it is desired that the article be attached by means of a chain which may be unreeled for use of the article and then when use is completed the chain will be reeled and the device will support the article on the clothing.

Usually an article of this character must be positioned in a vertical plane and in a certain definite location in order that the catch for the pawl may be positioned to engage the pawl which will fall into engagement with the catch when in one position. Thus, if the device is placed in a horizontal plane as it is sometimes desired that the same shall be positioned, the pawl will not fall by gravity into position and therefore will not properly operate. Centrifugal force is utilized for throwing the pawl to release itself from the catch with which it engages and accordingly any resilient means for moving the pawl becomes very delicate and precision-like.

One of the objects of this invention is to provide a reel which will operate in a horizontal plane as well as in a vertical plane.

Another object of the invention is to provide non-resilient means for urging the pawl to engage the catch when in horizontal position.

Another object of the invention is to provide a simple finger raised from the stock of the reel for utilizing gravity for urging the pawl in the direction desired.

With these and other objects in view, the invention consists of certain novel features of construction, as will be more fully described, and particularly pointed out in the appended claims.

In the accompanying drawings:

Figure 1 is a plan view of the face of the device;

Figure 2 is a view similar to Figure 1 but showing the back of the device;

Figure 3 is an edge view of the device;

Figure 4 is a central sectional view;

Figure 5 is a section on line 5—5 of Figure 4;

Figure 6 is a view similar to Figure 5 but illustrating the reel and pawl in a different position;

Figure 7 is a sectional view on line 7—7 of Figure 5.

In proceeding with this invention, I have raised an arm from the stock of the metal reel upon which the chain is wound and upon which the pawl rests so that while in the horizontal position the pawl will slide down the inclined position of the arm toward engaging position with the catch on the spindle, thus making it unnecessary

for the device to be located in a certain definite position in order for latching to occur.

With reference to the drawings, 10 designates the bottom or back plate of the device which has a circular or cylindrical flange 11 adjacent its outer edge. A spindle 12 is fixed to the bottom plate by being reduced to provide a shoulder 13 and is then passed through the bottom plate and headed as at 14. A cup 15 is located beneath this spindle and is secured in position by securing the spindle in place. This cup is provided with a plurality of notches into one of which the end of a spring of the reel is received to hold the spring with reference to the plate. The spindle is cut away at its outer end as at 16 to provide a flat surface or catch 16 for purpose to be presently described.

A reel designated generally 17 is formed from two pieces of sheet stock 19 and 20 which are brought into face-to-face engagement. These sheets are bent outwardly to provide the cylindrical surface 21, 22 with flanges 23 and 24 extending outwardly from this cylindrical surface so as to receive a chain or other flexible member 25 in this channel so formed. A recess 26 in the plate 19 provides a chamber for the spiral ribbon spring 27 which has its end in the outer convolution secured to the reel while its inner end 27' is received in one of the notches in the cup 15 to hold it fixed relative to the spindle 12. The stock of this plate 19 is also drawn outwardly as at 28 so as to provide a bearing on the spindle 12 for rotation of the reel on the spindle.

The plate 20 of the reel also provides a recess 29 into which the spindle 12 projects and in which the cut away portion forming the catch 16 is located. The bottom wall of this recess has a pivot pin 30 raised therefrom and upon this pin a pawl 31 is pivoted. This pawl is notched to provide a surface 32 which may engage the flat surface 16 of the catch provided on the spindle and when so engaged the reel is prevented from rotation on the spindle in the direction in which it is urged by the spring. However, when the chain 25 is pulled to rotate the reel on the spindle the spring is wound up and in some positions the pawl 31 which is carried with the reel will be free from the catch. If the chain is then released, the spring will cause a winding rotation of the reel and the pawl will be thrown outwardly by centrifugal force so that it will not engage the catch 16.

It is found, however, that some means are necessary in order that the pawl may engage the catch when in a horizontal plane even when

3

the reel is permitted to revolve slowly. Accordingly, I have raised a finger 35 from the sheet stock of the plate 20 of the reel as shown in Fig. 7 so that the detent 34 of the pawl will ride on the inclined surface of this arm 35 which will slide the pawl downwardly along this inclined surface to cause the surfaces 32 and 16 to engage, this action taking place when the pawl is in a horizontal plane and is urged only by gravity. In order to prevent the pawl from extending outwardly beyond the arm 35 a finger 36 is raised at the end of the arm 35 so that the pawl will strike this finger and be prevented from undue outward movement. A cover 44 telescopes into the recess 29 to maintain the pawl in place on its pivot 30.

A cap 40 is telescoped over the flange 11 of the base so as to cover the whole and provide a nice outer appearance. This cap provides a face plate 41 and a flange 42, the latter of which telescopes the flange 11 while there is an opening 43 provided in the flange through which the chain 25 may extend for being withdrawn to cause rotation of the reel and a winding of the spring 27 for retracting the chain when released.

I claim:

1. In a reeling device a spindle having a catch therein, a spool rotatably mounted on said spindle, a spring for rotating said spool on said spindle in one direction, a pawl pivoted on said spool at a point radially outward from its axis to engage said catch and prevent rotation of the spool under influence of the spring, and a mem-

ber on the spool adjacent the free end of the pawl having an inclined surface on which the pawl rests to urge the pawl under the influence of gravity inwardly to engage said catch when in substantially a horizontal plane.

2. In a reeling device as in claim 1 wherein a stop limits the outward movement of the pawl along said inclined member.

3. In a reeling device as in claim 1 wherein a stop is located at the outer end of the inclined surface of said member.

4. In a reeling device as in claim 1 wherein said member is an arm raised from the stock of said reel.

5. In a reeling device as in claim 1 wherein said member is an arm raised from the stock of said reel and a finger is bent from said arm to form a stop.

LESTER W. BALLOU.
